UNITED STATES PATENT OFFICE.

JOHN J. DONOVAN, OF OAKLAND, CALIFORNIA.

WINDOW.

Application filed October 1, 1923. Serial No. 665,859.

This invention relates to windows and especially to a mounting or connection between the window sashes and frames whereby the sashes may be swung about a vertical support or axis to assume a closed or open position.

The object of the present invention is to generally improve and simplify the construction and operation of window mountings of the character described; to provide a mounting which permits the sashes to swing about a vertical axis which constantly changes position as the sashes are opened or closed; a mounting which is connected both to the upper and lower rails of the sashes, thereby forming a substantially rigid connection between the sashes and the casing or frames; a mounting which is simple in construction, easy to install, and which is completely hidden between the sashes and the frames when the sashes are closed, and as such protects the mountings against rain and weather action; a mounting which permits complete reversal of the sashes, thus permitting ready cleaning of both exterior and interior surfaces of a window when necessary; and further, to provide means for locking the windows when in open position.

One form which my invention may assume is exemplified in the following description and illustrated in the accompanying drawings, in which—

Fig. 1 is a central vertical section of a window and casing showing the application of the invention.

Fig. 2 is a perspective view of the mounting which is disposed between the window sash and the sill of the casing.

Fig. 3 is a perspective view of the mounting disposed between the window sash and the head of the casing.

Fig. 4 is a plan section of a window sash and casing showing a semi-reversible type of mounting.

Fig. 5 is a perspective view of the mounting employed in connection with the semi-reversible type.

Fig. 6 is a plan section of a window sash and casing showing the sash reversed.

Referring to the drawings in detail, and particularly to Figs. 1, 2 and 3, A indicates in general a window casing, 2 the head, and 3 the sill thereof. Disposed between the head and the sill is a window 4 which is carried by a sash of the usual construction. Disposed between the upper rail of the sash

and the head 2 of the casing is a mounting such as shown in Fig. 3, and disposed between the sill 3 and the lower rail of the window sash is a mounting such as shown in Fig. 2.

The mounting shown in Fig. 2 consists of a metal plate B which extends from end to end of the sill. The plate consists of a base portion 5, a track or channelled portion 6, 65 and a front lip or flange 7, the plate being secured to the sill by screws or other means and as such is stationary. The sill is recessed to receive the plate B and the inner section of the sill indicated at 8 is extended 70 a slight distance over the sill to cover and enclose the track portion 6. The lower rail of the sash is similarly recessed as shown at 9 and thus covers or encloses the arms and guide shoes hereinafter to be referred to, 75 thus protecting the same against rain and weather action; that is, by recessing the rail as shown at 9 a front lip 10 is formed and all parts of the mounting are thus enclosed and covered when the window is closed.

Slidably mounted on the plate B is a shoe generally indicated at 11; this shoe being provided with a pair of upwardly extending lugs 12 which enter the track 6 and are guided thereby. Pivottally mounted on the outer end of the shoe as at 13 is a hinge-arm 14.

This hinge-arm is secured to the lower rail of the sash and the sash or window will thus swing in unison with the hinge-arm 14 when sliding movement is imparted to the shoe 11. A second arm is also employed as indicated at 15; this arm being pivotally attached to the plate B as indicated at 16 at one end and it is similarly pivotally attached to the outer end of the hinge-arm 14 95 as indicated at 17. The upper mounting is somewhat similar to the lower mounting; that is, the head 2 is channelled to receive a channel-shaped track such as indicated at 18; this being secured in the head by screws or other means. A hinge-arm 14^a is secured to the upper rail of the sash and a second arm 15^a is pivotally secured at one end to a plate

19, and its opposite end is pivotally secured to the hinge-arm 14^a as indicated at 17^a. The inner end of the hinge-arm 14^a is provided with a pin 20 and this extends upwardly into the channel-shaped track 18 and is guided thereby. The upper rail of the sash is recessed for the purpose of concealing the arms 14^a and 15^a when the sash is in closed position.

From the foregoing description it should be understood that the arms 14 and 14^a are rigidly secured to the upper and lower rails of the sash and that the sash or window is thus free to swing about a constantly changing vertical axis when moved to open position or vice versa when closed; that is, one end of the sash is stabilized by the arms 15 and 15^a, while the other end of the window is supported and guided by the shoe 11 and the pin 18.

If when standing inside of a room one pushes outwardly on the left hand side of the window, it is obvious that the shoe 11 and the pin 18 will move along their tracks towards the left hand side of the casing and that the hinge-arms 14 and 14^a will assume a right angular position with relation to the sill and head when the window is completely open, while the arms 15 and 15^a will assume an angular position with respect to arms 14 and 14^a. It can furthermore be seen that the right hand side of the sash may be grasped at this point and swung towards the left hand side of the casing, thus reversing the window; the position of the window, the shoe and the arms 14 and 15 when the window is completely reversed being shown in Fig. 6.

30 A mounting which permits complete reversal of the window is of considerable importance as it permits ready cleaning of both sides of the window without resorting to the usual practice of leaning out when washing 35 and cleaning the same. The same is true when the sash opens from the right hand side as the equipment is applicable for sash opening either on the right or left side.

By referring to Fig. 2 it will be noted that the outer face of the track portion 6 is provided with a series of notches or recesses such as indicated at 25, and that a latch or bolt 26 is mounted on the shoe 11, which may be moved into or out of engagement 45 with the notches 25 by means of a pivotally mounted lever 27. This is also of considerable importance as it permits locking of the window in a number of open positions, thus preventing slamming or closing of the window if it should happen to be stormy, windy 50 or otherwise. The latch or bolt 26 which is disposed transversely of the rail 6 is mounted on and carried by one arm of the latch lever 27 disposed longitudinally of the rail 55 and pivoted intermediate of its ends to the triangular shoe to form two arms, the bolt being mounted on one arm and the other arm being provided with an upwardly extending terminal operating portion. One of the 60 lugs 12 of the shoe forms an abutment for the latch bolt when the latter is engaged with one of the notches 25 of the lower track.

65 By referring to Figs. 4 and 5, a slightly modified form of the structure is shown; that is, the track indicated at C is only extended

slightly beyond one-half the length of the sill and there stopped. This type of mounting is employed where a semi-reversible window is desired; that is, the window can be swung from closed position to complete open position, but it cannot be completely reversed as shown in Fig. 6. The mounting is otherwise practically identical; that is, arms 15^b and 14^b are employed, but the sliding shoe is eliminated; the hinge-arms 15^b being cut 75 away at their inner ends as shown at 30 and being provided with a pin 31 to engage the guide rail; the plate 32 being secured to the sill in any suitable manner to pivotally support the arms 14^b.

80 From the foregoing description it can be seen that the upper and lower mountings form a substantially rigid connection between the window casing and the sash, and that the mountings employed are completely 85 enclosed and protected against rain and weather when the sash or window is closed.

It can furthermore be seen that the mechanism or mounting employed is exceedingly simple, cheap to manufacture, and easy to 90 install, and that a standard form of casing and sash construction may be employed; the only change required being the recessing of the head and sill and the upper and lower 95 rails of the sash as previously stated.

When a mounting such as shown in Figs. 1, 2 and 3, is employed, complete reversal of the window is permitted, thus facilitating washing of the windows and eliminating all 100 danger in connection therewith, and where complete reversal is not required, the mountings shown in Figs. 4 and 5 may be employed. Even with such a mounting it is fairly easy to wash the windows as both sides can be 105 readily reached without excessive leaning out of the window.

In connection with the semi-reversible type of mounting, I wish it understood that this may be employed in connection with transoms, horizontally swinging windows, 110 awning or projector type windows, and the like. In such cases the guide rails and arms are secured to the sides of the casing or door frame and the transom or window may thus be swung about a horizontal axis.

115 Having thus described my invention, what I claim and desire to secure by Letters Patent is—

In combination, a window frame, a sash mounted therein, a lower track secured to 120 the sill of the frame and having an upwardly extending inverted U-shaped flange forming a channel open at the front and provided thereat with a plurality of spaced notches, a pair of hinge arms normally disposed at an 125 angle to each other and pivoted together at the angle, one of said arms being pivoted at the outer end to the said track, a triangular shoe slidable along the track and extending into the opening at the front of the channel 130

and having upwardly extending lugs entirely spaced apart and engaged with the channel interiorly thereof to provide a two point bearing, said shoe being pivoted to the other 5 of said pair of hinge arms, means for securing the sash to the hinge arm, which is slidably connected to the channel, a latch lever pivoted intermediate of its ends to the shoe and extending longitudinally of the

channel and provided at one end with 10 an operating portion, and a latch bolt carried by the other end of said lever and disposed transversely of the track and adapted to engage said notches, one of the lugs forming an abutment for the bolt and the latch lever 15 and bolt being concealed by the sash when the latter is in its closed position.

JOHN J. DONOVAN.
